UNITED STATES PATENT OFFICE.

JESSE M. ZIMMERMAN, OF WILKINSBURG, PENNSYLVANIA, ASSIGNOR TO WESTINGHOUSE ELECTRIC & MANUFACTURING COMPANY, A CORPORATION OF PENNSYLVANIA.

RELAY OPERATION INDICATOR.

Application filed March 1, 1924. Serial No. 696,184.

My invention relates to relays and particularly to operation indicators therefor.

One object of my invention is to provide a relay operation indicator that shall serve 5 to indicate when a predetermined operation has been effected within the relay.

Another object of my invention is to provide an indicator, of the character described, that shall be applicable to relays at 10 present in service without changing the structure of the relays.

A further object of my invention is to provide an operation indicator, having resetting means, for relays of the induction type 15 that are provided with covers, in order that the resetting means may be easily assembled on the cover to permit resetting of the indicator from the outside of the cover, thereby obviating the necessity of removing the 20 latter.

My invention is an improvement upon the structure shown and described in the application of Harvey P. Sleeper, Serial No. 624,299, filed March 10, 1923, and assigned 25 to the Westinghouse Electric & Manufacturing Company. In that application, there is disclosed an operation indicator comprising a semaphore and an electromagnet for actuating the same to its indicating position when a predetermined operation is 30 effected in the relay.

In order to reset the semaphore to its initial position, in which position it is not visible, there is provided a resetting mechanism comprising an arm normally biased to a position that is out of 35 the path of movement of the semaphore, a sleeve extending through the glass cover of the relay that is adapted to slip over the supporting rod for the glass cover, and an operating member for the sleeve comprising 40 a washer element similar to that ordinarily employed and secured to the outer end of the sleeve to permit turning thereof to reset the semaphore. The usual thumb nut is provided 45 to tighten the glass cover to the base casting of the relay and the outer appearance of the relay is in no way changed. The resetting element comprising the sleeve, the resetting arm and the outside washer may 50 be easily assembled on the glass cover since the holes that are ordinarily provided in the cover are sufficiently larger than the supporting rod to accommodate the sleeve.

In accordance with my invention, a brad-

ing member is so interposed between the 55 thumb nut and the glass cover that the operation of the resetting member is not interfered with by reason of frictional engagement between the thumb nut and the sleeve.

In the accompanying drawings,

Figure 1 is a plan view, partially in elevation and partially in section, of a portion of a relay of the induction type illustrating the disposition of the operation indicator and the resetting mechanism therefor,

Fig. 2 is a front view, partially in elevation and partially in section, of a portion of the relay that is illustrated in Fig. 1, and

Fig. 3 is a detail view of the resetting mechanism with parts broken away.

My invention comprises, in general, a relay 1 that is provided with an operation indicator in the form of an electromagnet 2 that actuates a semaphore 3 to a position behind an aperture 4, and a resetting mechanism 5 that is mounted on a clamping bolt 6 that supports the cover or casing 7 of the relay 1.

The semaphore 3 is provided with a tail piece 8 that is engaged by an arm 9 of the 80 resetting mechanism 5 for the purpose of moving the semaphore 3 away from behind the aperture 4 when it is desired to reset the indicator device.

The arm 9 is normally biased into its 85 lower position by a coil spring 11 mounted around a sleeve or tubular member 12 that fits loosely over the bolt 6 and extends through the casing or cover member 7 of the relay. The cover member 7 of such a 90 relay is generally of glass in order to permit ready inspection of the relay parts and the semaphore. The sleeve 12 is provided, at its inner end, with a cap piece 13 for the attachment of the arm 9 after the insertion 95 of the sleeve 12 through the cover member 7.

Exteriorly of the cover member 7, the sleeve 12 terminates in a knob 14 that provides a knurled or gripping surface for the manipulation of the resetting device 5. A 100 washer 15 of fabric material is inserted between the cover member 7 and the knob 14 in order to prevent the access of dust and moisture into the relay 1.

A bracing member 16 of substantially U- 105 shape is placed on the bolt 6 exteriorly of the knob 14, but not in frictional engagement therewith. The usual thumb nut 17 is

provided exteriorly of the bracing member 16 for engagement with a threaded portion 18 of the bolt 6. If desired, overturned lugs 19 on the thumb nut 17 may extend through the perforation of the bracing member 16, so that the two parts constitute a unitary structure.

It is to be observed that the knob 14 is entirely independent of, and out of frictional engagement with, any part of the bracing member 16 or the thumb nut 17. This feature is of extreme importance for the reason that for correct performance of the relay 1, the cover member 7 should be tightly secured 15 in position and where the knob 14 and the thumb nut 17 are in engagement, frictional engagement therebetween interferes with the operation of the knob 14 and the sleeve 12.

Assuming the relay to be energized, but 20 below a predetermined value, the relation of the parts will be that shown in the figures of the drawing. Upon the occurrence of predetermined conditions in the relay, the electromagnet 2 is actuated and the semaphore 25 3 is drawn into position behind the aperture 4. The relay 1 may simultaneously operate connected circuit interrupters or other protective devices (not shown).

Where a large number of relays are 30 mounted on a single switchboard, the operator may quickly locate the relay that operated by an inspection of the various indicating devices 2. Having located the operated relay, the operator grasps the knob 14 and gives it a slight clockwise turning movement against the action of the spring 11 whereupon the arm 9 moves to the position shown in broken lines to engage the arm 8 of the indicator to cause the semaphore 3 35 to turn in a counter-clockwise direction away from behind the aperture 4. As soon as the operator releases the knob 14, the arm 9 returns to its lower position by reason of the action of the spring 11 and without interference from the thumb nut 17 and bracing member 16. The parts are then in the position shown in the figures of the drawing and are ready for another operation of the relay.

While I have shown and described my invention as operatively connected with a relay, it is to be understood that this showing is only by way of illustration. My invention is applicable to any device where a perforated member is held in position by a 50 clamping bolt and an indicator on one side of the perforated member, is to be operated from the other side thereof.

I do not wish to be restricted to the specific circuit connections or arrangement of parts 55 herein set forth, as various modifications thereof may be effected without departing from the spirit and scope of my invention. I desire, therefore, that only such limitations shall be imposed as are indicated in the ap- 60 pended claims.

I claim as my invention:

1. In an instrument, the combination with a transparent cover member, a clamping bolt therefor and an indicator enclosed thereby, a resetting device for said indicator co-operating with said bolt, an actuating device for the resetting mechanism comprising a member loosely fitted on said bolt and extending through the cover member, and a clamping element engaging the cover member and mounted on the bolt independently of the actuating device to permit movement of the actuating device independently of the clamping element. 70

2. In an instrument, the combination with a transparent cover member, a clamping bolt therefor and an indicator enclosed thereby, a resetting device for said indicator co-operating with said bolt, an actuating device for the resetting mechanism comprising a member loosely fitted on said bolt and extending through the cover member, thereby constituting a gripping surface, and clamping means mounted on the bolt outwardly from, but independent of, the actuating device and bridging said device to engage the cover member, thereby permitting movement of the actuating device independently of the clamping means. 80

3. In combination, a perforated member 90 having a transparent portion, a clamping bolt passing through the perforation, an indicator, resetting mechanism for the indicator co-operating with the bolt, an actuating device for the resetting mechanism comprising a member loosely fitted on the bolt and passing through the perforated member thereby constituting a gripping surface, a clamping means mounted on the bolt and a bracket between said clamping means and said cover member and bridging said gripping surface to permit movement of the gripping surface independently of the clamping means. 100

4. In an electrical relay, a perforated transparent cover member, a clamping bolt passing through the cover member, an indicator, resetting mechanism for the the indicator co-operating with the bolt, an actuating device for the resetting mechanism comprising a member loosely fitted on the bolt and passing through the cover member thereby constituting a gripping surface, a clamping means mounted on the bolt outside said actuating device and means for transmitting the pressure of the clamping means to the cover member and shaped to permit the application of a moving force to the actuating device without disturbing the clamping means. 110

In testimony whereof, I have hereunto 120 subscribed my name this 18th day of February, 1924.

JESSE M. ZIMMERMAN.
